UNITED STATES PATENT OFFICE.

HANS O. WESTMARK, OF AURORA, ILLINOIS, ASSIGNOR OF ONE-HALF TO
ORVILLE C. MANN, OF NORA SPRINGS, IOWA.

BOILER-FLUE RATTLER.

SPECIFICATION forming part of Letters Patent No. 714,344, dated November 25, 1902.

Application filed October 1, 1901. Serial No. 77,201. (No model)

To all whom it may concern:

Be it known that I, HANS O. WESTMARK, a citizen of the United States, residing at Aurora, in the county of Kane and State of Illinois, have invented certain new and useful Improvements in Boiler-Flue Rattlers, of which the following is a specification, reference being had to the accompanying drawings, forming a part thereof.

10 The purpose of this invention is to provide a machine for rattling boiler-flues for the purpose of detaching scale and other incrustations which result from their use in boilers supplied with water containing large quantities of lime and other minerals, from which the incrustation is formed.

15 The invention consists in means for tumbling the flues in a chamber adapted, preferably, to contain water sufficient to cover the flues in the process, so that dust arising from the process is prevented and also the noise is deadened and muffled, while at the same time the incrustation is partly dissolved and rendered more easy of detachment by the 20 action of the water.

25 It consists also in means for tumbling the flues in a receptacle without rotating the receptacle and means for delivering them thereinto conveniently from a loaded car and for delivering them therefrom conveniently and substantially without handling onto a car by which they may be removed.

It consists, further, in details of construction which are set out in the claims.

30 In the drawings, Figure 1 is a transverse vertical section of my improved flue-rattler and its foundation-supports. Fig. 2 is an end elevation of the same, the track and approaches thereto and the pit and foundation-walls being shown in vertical section. Fig. 3 is a vertical longitudinal section at the line 33 on Fig. 1. Fig. 4 is a top plan. Fig. 5 is a detail section at the line 55 on Fig. 1, showing a movable head adjustable according to 35 the length of the flues which are being handled. Fig. 6 is a detail elevation of the deflector-terminal and detent-dogs. Fig. 7 is a detail plan of drum connections.

My improved rattler comprises a cradle consisting of bars A, suitably supported in parallel position, defining the outline of a semi-

cylindrical receptacle in which the flues to be cleaned may lie and be rolled transversely. The means of thus operating the flues consists of a shaft B, extending longitudinally 55 above the cradle at the center of the semi-cylindrical receptacle defined by the cradle-bars and having any desired number of sweep-arms C secured to it and revolved by it, sweeping transversely through the semicy- 60 lindrical cradle, so as to carry the flues lying therein up at one side of the shaft and permit them to fall over at the other side back into the cradle. The cradle's outlines are continued, necessarily, at one side up above 65 the horizontal diameter to retain the flues on the sweep-arms as they rise. This is done by the use of the curved bars D, which for another purpose (hereinafter explained) are secured to a longitudinal shaft E, about 70 whose axis they may be swung slightly, but which holds them normally in position, so that their inner concave faces correspond to the cylindrical outline of the cradle and to the path of movement of the sweep-arms. These 75 bars D extend up on the side of the cradle at which the sweep-arms rise, the bars keeping the flues on the sweep-arms until they are lifted so high that they tend to roll down inward and fall into the cradle at the opposite 80 side of the shaft from that on which they were lifted by the sweep-arms. Preferably the sweep-arms are two in number, extending in diametrically opposite directions and being integral with each other, as shown in the drawings, so that as the flues are carried upward at one side past the horizontal diameter far enough so that they tend to roll down on the arms they may be guided by the arms and kept thereon in their whole advancing movement, and thus practically kept under control, rolling upon each other as they roll upon the sweep-arms and never falling as a mass bodily without support, as they might otherwise be liable to do, with danger of becoming 90 crossed and tangled in falling. I do not limit myself, however, to two sweep-arms; but any desired number may be employed, the sweeps being arranged, preferably, at equal intervals about the shaft. The sweep-arms, however, 95 preferably have webs or flanges b b, upon which the flues rest and roll, said flanges be-

ing widened at the center, so as to direct the flues past the shaft. Each pair of sweep-arms is preferably made of two parts cast from the same pattern and symmetrical about a plane 5 transverse to the axis of the shaft, so that they may be applied to each other in reverse position and bolted together upon the shaft. The sweep-arms thus produced have the edge 10 outline of the pipe-supporting webs, at one side curved concave forward in the direction of the pipe-encountering movement of the arms, the other edge being approximately straight and radial. This form tends to cause the flues to start rolling down past the shaft 15 as soon as they pass above the level of the same and to prevent those near the outer end from being thrown by the sweep-arms or being delayed in starting down so long as to be liable to fall abruptly when they do start. 20 The cradle formed of the bars A is within a chamber adapted to contain water, such chamber being semicylindrical, widened at the top by flaring lateral extensions of the curved wall. The preferred construction is that 25 shown in the drawings, in which the water-containing chamber is made in sections F F F, of which the web f constitutes the wall of the chamber and flanges f' f'' means of securing successive sections together, so as to make a 30 chamber of any desired length, the ends being formed by plates G G, bolted or riveted to the outer flanges of the outermost sections. These cast sections constituting the chamber may be formed with bosses F' F'', &c., 35 projecting radially inward from their web f at intervals over the semicylindrical portion to support the cradle-bars A A A, which are bolted thereto, as illustrated. Inclined approaches to the semicylindrical portions of 40 the cradle are formed at their opposite sides by the inclined extensions A' and A'' of the cradle-bars A, the former being at the entrance side and adapted to guide the flues down into the cradle and the latter being at 45 the delivery side, forming part of the guideway by which they are delivered from the cradle and lying flat upon the flaring lateral extensions F' and F'' of and corresponding to the sections F F F of the main cylindrical 50 portions of said chamber.

K and L are brackets mounted on the foundation-walls M for supporting the extensions F' and F'', respectively.

T T are I-beams extending longitudinally 55 above the cradle, resting on the masonry walls at the opposite ends, being located high enough to be beyond the sweep of the sweep-arms. On these I-beams are mounted the rails U U of a track on which cars may run to a 60 position directly above the cradle for the purpose of delivering the flues into the latter, the delivery being made by rolling the flues off sidewise from the cars, so that they may fall onto the inclined end portions A' A'' of 65 the cradle-bars.

B' B'', &c., are brackets which may be provided bolted to the outer side of the rails B on

the receiving edge of the cradle, these brackets having webs B¹⁰, whose edges, standing parallel with the upper faces of the cradle-bars 70 at a distance inward therefrom sufficient to afford passage-way for the largest-sized flues which will be handled in the cradle, define a channel or throat a', through which the flues roll into the cradle when they fall laterally 75 from the car. Preferably the space between the track-rails and outside the same to the edge of the brackets D² at the receiving side and to the path of the flues between the arms D' and O at the delivery side is covered over 80 by a floor W. The bracket W' may be mounted on the flooring at the outside of the track at the receiving side, having inclined upper edges to guide the flues as the fall from the car into the throat or channel a', and at the 85 opposite side of the mouth of said channel there may be mounted upon the masonry inclined guide-brackets W³ W³ to guide the flues from the outer side back into the inlet-channel. The bars D, which constitute the upper portion of the cradle at the delivery side, but above the point of delivery, are formed as 90 terminals of arms D', formed with cylindrical bosses D¹⁰, apertured to receive the square shaft E, journaled in the head-plates G G. 95 The shaft may be rocked to carry the bars D D from the position at which their inner faces correspond with and constitute a continuation of the cylindrical outline of the cradle to position shown in full line in Fig. 1, at which 100 the lower pilot-points d of said bars D protrude inward into the space of the cradle and overhang the path of the outermost row or layer of flues carried upward by the sweep-arms. In this position the lower edge of the arm 105 D' is parallel with the outwardly-deflected portions A² of the cradle-bars A, so that there is formed between said deflected cradle-bars and said arms D' an inclined passage-way leading upward and outward from the cradle-space. The arms D' extend past the bosses 110 D¹⁰ in a curved direction, and on the upper inclined face of the flaring walls F'', which constitute the continuation of the water-chamber at the delivery side, there are mounted 115 and made rigid upstanding guide-bars O, which are curved to correspond with the curvature of the arms D' and parallel therewith at the position occupied by said arms when the bars D are set protruding their lower or 120 pilot-points d into the cradle-space to engage and deflect the outermost row of flues. There is thus formed a guide-channel for the flues, in which they are conducted upward when they are pressed from behind by the sweep-arms, which occurs when the direction of rotation of the shaft is reversed, for which provision is made in the driving mechanism. To the upper ends of the arms D' and upstanding bars O O there are secured extensions P and Q, respectively, curved so as to be parallel and constitute a continuation of 125 the guideways for the flues, by which they are secured to the outer side of the rails B on 130

so as to be delivered from the upper end of such guideways downward by gravity onto cars prepared to receive them standing on the tracks above the cradle. The upper ends 5 of the arms D' and bars O are provided with terminals D'' and O' at the lower ends of the curved guides P and Q, having square sockets, adapting them to be lodged on said square terminals. These terminals and sockets are 10 of the same dimensions, so that the parts P and Q are interchangeable, and being interchanged or transposed may be set in reversed position, so as to curve outward instead of inward, and made to deliver the flues laterally 15 outward onto cars standing on outside track.

In order to insure the separation of the outer layer or row of flues from the remainder as the sweeps carry them up at the delivery side and to prevent the lower point of the deflector D from colliding with the flues of the next inner row instead of entering between them and separating them, I provide on the back side of the sweep-arm lugs or parting-fingers b b at such distance back from the end 20 as to leave room for one flue between them and the cradle-bars A, the presence of these fingers projecting substantially the diameter of the flues, so that the flues of the second row or layer are prevented from lodging 25 deeply between the flues of the next inner layer, and are thus held in position such that the pilot-point d of the deflector D readily enters between the outer and next inner row or layer of flues. In order prevent the flues 30 from being able to return into the cradle after having been forced out into the discharge-passage, I provide at the entrance of said passage, pivoted to the deflectors D, dogs S S, &c., adapted by their form to hang normally in position to close the passage, as seen in Fig. 1, 35 and stopped in that position against movement inward in respect to the cradle by the shoulder d² of the deflector near the pivot of the dog, but free to swing in the other direction to allow the flues to pass them as they are forced outward. Any flue which is carried 40 beyond the dog is prevented from returning, and thus in each sweep of the sweep-arm after the deflector is set so as to open the discharge-passage all the flues in the outermost row or 45 layer will be forced into the passage, and this process will be continued each time the arm passes the deflector until the flues are all contained in a single row and are all delivered past the dog. To complete the delivery out 50 of the discharge-channel, any convenient means operated by hand may be employed.

In order to provide for delivering the flues to the rattler at the same side from which 55 they are discharged therefrom whenever this may be more convenient, the guides P being removed and the guides Q being left in place on the upper ends of the guide-bars O, inclined bars X X being substituted in the 60 sockets at the sides of the cars for the retaining-stakes which are employed to keep the load on the cars, the flues may be allowed to

move down such inclined bars, and are thereby directed into the guide-passage between the bars D' and O and follow the same down 70 into the cradle. In order to load the rattler at this side, it is necessary to provide for holding the dogs F F out of the channel, and for this purpose all the dogs are preferably mounted on a single shaft, journaled in the 75 deflectors B, the shaft having a lever-arm near one end, which can be reached from above to rock the shaft and carry the dogs out of operating position.

In order that flues of different diameters 80 within limits may be properly discharged upward through the passage-way formed by the bars D' and O without danger of becoming choked or jammed therein when they are of considerably less diameter than the full width 85 of the passage-way, I provide the arms D' and P with adjustable face-plates D¹² and P', respectively. The face-plate D¹⁰ is held out from the arm D' by springs d¹⁰, lodged in pockets provided for them in the arms D', and 90 said plate is drawn back to any degree necessary by screws D¹¹ D¹¹, retained by nuts d¹¹ at the back side of the arm D', by which any desired adjustment is made. The guides P and Q may be similarly provided with face- 95 plates p and q, held to said guides, respectively, by yielding strips p' and q', which tend to hold them in against the face of the guides by screws p¹⁰ and q¹⁰, being set through the guides to force the plates off therefrom 100 to any desired degree to narrow the passage for the flues.

The means for rotating the shaft B is seen in Figs. 2 and 5, comprising two sprocket-wheels B² B² on the shaft B outside the cradle 105 and its chamber and a counter-shaft B², having loose sprocket-pinions B³ B³, which has feathered on it a clutch-collar B⁴ between the pinions, said collar being adapted by familiar means (not illustrated) to be shifted into 110 engagement with either of the pinions at will. The chain B⁵ from one of the pinions passes directly about one of the sprocket-wheels B². The chain B⁶, passing around the other wheel B² and about the idle sprocket-wheels B⁹ and 115 B¹⁰, is diverted about the other pinion B³, which engages the back side of the chain to communicate motion through the chain, which thus derives motion in opposite direction from chain B⁵. The counter-shaft b² is driven by 120 chain B⁷, passing about the wheel B⁸ on said counter-shaft, deriving power from any source. (Not shown.)

I claim—

1. A boiler-flue rattler, comprising a horizontal cradle; a shaft extending longitudinally above the cradle, and means for rotating it; sweeps or carrying-arms on such shaft for lifting the flues as the arms rise upon one side of the shaft, and allowing them to fall as the arms descend upon the other side.

2. A boiler-flue rattler, comprising a horizontal cradle for the flues; a shaft extending longitudinally above the cradle, and means

for rotating it; sweeps or carrying-arms on such shaft for lifting and dropping the flues as the shaft rotates; and means for keeping the cylinder supplied with water during such 5 rotation.

3. A boiler-flue rattler, comprising a horizontal cradle for the flues; a revolute shaft extending longitudinally above the cradle; sweep-arms on the shaft for carrying the flues 10 up at one side and dropping them at the other side of the shaft; the cradle having at one side a delivery-channel, and a gate closing the mouth of such channel and adapted to be opened at will to permit the flues to pass thereinto from the cradle.

4. A boiler-flue rattler, comprising a horizontal cradle for the flues; a revolute shaft extending longitudinally above the cradle; sweep-arms on the shaft for carrying the flues 15 up at one side and dropping them at the other side of the shaft; the cradle having at the side at which the flues are carried upward a delivery-channel, and a gate closing the mouth of such channel and adapted to be opened at 20 will to permit the flues to pass thereinto from the cradle.

5. A boiler-flue rattler, comprising a horizontal cradle for the flues; a revolute shaft extending longitudinally above the cradle; sweep- 25 arms on the shaft for carrying the flues up at one side and dropping them at the other side of the shaft; a delivery-channel leading from the cradle at the side at which the flues are carried up by the sweep-arms; and a deflector 30 adapted to be intruded into the cradle at the upper margin of the mouth of said channel, to engage the outermost flue on said sweep-arms and deflect it to the channel.

6. A boiler-flue rattler, comprising a horizontal cradle for the flues; a revolute shaft 35 extending longitudinally above the cradle; sweep-arms on the shaft for carrying the flues up at one side and dropping them at the other side of the shaft; a delivery-channel leading 40 from the cradle at the side at which the flues are carried upward; a gate for closing the mouth of the channel, arranged to protrude into the cradle, when moved to open the mouth 45 of the channel, and adapted when in such position to engage and deflect into the channel the outermost flue carried by the sweep-arms.

7. A boiler-flue rattler, comprising a horizontal cradle for the flues; a revolute shaft 50 extending longitudinally above the cradle; sweep-arms on the shaft, adapted to lift the flues at one side and drop them at the other side of the shaft; the cradle having a delivery-channel leading from the side at which the flues are lifted; a gate for closing the 55 mouth of such channel, having a terminal which is carried inward with respect to the cradle when the gate is open to admit the flues to the channel; said terminal being formed and adapted to act as a deflector engaging the outermost flues on the arm and guiding them into the channel.

8. A boiler-flue rattler, comprising a hori-

zontal cradle for the flues; a revolute shaft extending longitudinally above the cradle; sweep-arms on the shaft to lift the flues at 70 one side and drop them at the other side of the shaft; a delivery-channel leading from the cradle at the side at which the flues are carried upward, said channel trending upward from its mouth, and a trip dog or latch 75 extending yieldingly into the channel near its mouth, adapted to yield to permit the flues to pass it, and to retain the same when they have passed it.

9. A boiler-flue rattler, comprising a horizontal cradle for the flues; a revolute shaft extending longitudinally above the cradle; sweep-arms on the shaft to lift the flues at 80 one side and drop them at the other side of the shaft; a delivery-channel leading from the cradle at the side at which the flues are carried upward, said channel trending upward from its mouth; a deflector adapted to be intruded into the cradle at the upper margin of the mouth of said channel, to engage 85 the outermost flue on said sweep-arms and deflect it to the channel; and a trip-dog mounted on such deflector, and extending yieldingly into the channel near its mouth, adapted to yield to permit the flues to pass 90 it, and to retain the same when they have passed it.

10. A boiler-flue rattler, comprising a horizontal cradle for the flues; a revolute shaft extending longitudinally above the cradle; sweep-arms on the shaft for carrying the flues 95 up at one side and dropping them at the other side of the shaft; a delivery-channel for the flues leading from the cradle at the side at which the flues are carried upward therein; the sweep-arms having each a projection from 100 the edge which is forward in the path of movement of the arms, located at a distance from the flue-supporting surface of the cradle slightly greater than the diameter of a single 105 flue, whereby the outermost flue carried by the sweep-arms is parted from the next inner flue lying thereon; and a deflector, mounted on the cradle and adapted to be intruded thereinto at the upper side of the mouth of 110 the delivery-channel, to engage the outermost flue on the sweep-arm in the parting or gap provided by said lugs on the sweep-arms between the outermost flue and the next to deflect such outermost flue into the delivery- 115 channel.

11. A boiler-flue rattler, comprising a horizontal cradle for the flues; a track extending longitudinally above the cradle, and a charging chute or channel leading from a point at 120 one side of the track downward and inward into the cradle.

12. A boiler-flue rattler, comprising a horizontal cradle for the flues, and means operating therein to tumble the flues; a track extending above the cradle, longitudinally thereof, and a delivery-channel leading from one side of the cradle outward and upward, past the track, and thence extended upward

and inward, and having its delivery end overhanging the track.

13. A boiler-flue rattler, comprising a horizontal cradle; a revoluble shaft extending longitudinally above the cradle; sweep-arms on the shaft to carry the flues in the cradle up at one side and drop them at the other side of the shaft; a track extending longitudinally above the cradle, and above the range of the sweep-arms therein; a delivery-channel leading from the side of the cradle at which the flues are carried upward therein by the sweep-arms, such channel extending outward and upward past the track at one side thereof, thence on upward and inward, terminating at a position overhanging the track; whereby the flues are forced by the sweep-arms into said channel, and may be delivered thereby onto cars resting on the track above the cradle.

14. A boiler-flue rattler, comprising a horizontal cradle for the flues; a revoluble shaft extending longitudinally above the cradle; sweep-arms upon the shaft for lifting the flues at one side and dropping them at the other side of the shaft; a delivery-channel leading from the side of the cradle at which the flues are lifted, extending outward and upward past a horizontal plane above the sweep of the sweep-arms, and having further-extended portions adapted to extend upward in a path curved transversely with respect to the length of the cradle, said upwardly-extending portion being reversible so as to curve either inward or outward with respect to the cradle; whereby such delivery-channel is adapted to deliver the flues onto a carrier above the cradle or onto a carrier located one side thereof.

15. A boiler-flue rattler, comprising a horizontal cradle; a revoluble shaft extending longitudinally above the cradle; sweep-arms on the shaft to lift the flues at one side and drop them at the other side of the shaft; such cradle consisting of bars curved about the axis of the shaft, and constituting tracks upon which the flues may roll and slide laterally; and a half-cylindrical trough or chamber within which such cradle is constructed, the bars of the cradle being spaced and secured at a distance inward from the trough or channel, whereby space is provided beyond the sweep of the arms and the path of the flues lifted and dropped thereby, for the accumulation of scales broken from the flues in rattling.

16. A boiler-flue rattler, comprising a horizontal cradle; a revoluble shaft extending longitudinally above the cradle; sweep-arms carried by the shaft in its revolutions to lift the flues at one side and drop them at the other side of the shaft; the cradle having at one end a head to stop the flues longitudinally in one direction, and a movable head on

the shaft, adapted to be adjusted thereon, according to the length of the flues, to stop them in the opposite direction.

17. A boiler-flue rattler, comprising a horizontal cradle; a shaft extending longitudinally above the cradle; sweeps or carrying-arms on such shaft, for carrying the flues up at one side and down at the other side of the shaft; the cradle having at one side an upwardly-leading delivery-channel; means for rotating the shaft, adapted for reversing the direction of rotation at will; whereby rotation in one direction causes the flues to descend on the side at which the delivery-channel opens and to avoid entrance thereto, and rotation in the opposite direction causes them to ascend into and be discharged by way of said channel.

18. A boiler-flue rattler, comprising a horizontal cradle for the flues, a shaft extending longitudinally above the cradle, sweeps or carrying-arms on such shaft for carrying the flues up at one side and down at the other side of the shaft; such sweep-arms having their edges at one side adapted to permit the flues to roll freely inward thereon as the arms rise, and the edges at the opposite side having near their ends means for detaining the outermost flues against inward movement, the cradle having a delivery-channel leading upward from the side toward which the sweep-arms rise, revolving in direction to carry the last-mentioned edge forward.

19. A boiler-flue rattler, comprising a horizontal cradle for the flues; a revoluble shaft extending longitudinally above the cradle; sweep-arms on the shaft for carrying the flues up at one side and down at the other side of the shaft; the cradle having at one side a delivery-channel, and a gate closing the mouth of such channel, adapted to be opened at will to permit the flues to pass thereto; means for revolving the shaft, adapted for reversing its direction of rotation; the sweep-arms having toward the outer end, at the edge which is forward when the shaft is revolved in direction to carry the arm up at the side having the delivery-channel, means for detaining the outermost flue thereon as the arms rise.

20. A boiler-flue rattler, comprising a horizontal cradle for the flues, having an upwardly-extending delivery-channel formed by parallel guide-bars, the bars at one side of such channel having adjustable face-plates by which the width of the channel may be regulated to correspond to the diameter of the flues.

In testimony whereof I have hereunto set my hand, at Chicago, Illinois, this 18th day of September, A. D. 1901.

HANS O. WESTMARK.

In presence of—

CHAS. S. BURTON,
GEORGE H. WARNER.
